Primary Examiner — John Windmuller*Assistant Examiner* — John R Yeh*(74) Attorney, Agent, or Firm* — The Belles Group, P.C.(57) **CLAIM**

I claim the ornamental design for a dual electronic article surveillance-RFID tag, as shown and described.

DESCRIPTION

FIG. 1 is a top view of a dual electronic article surveillance-RFID tag in accordance with my new design; and, FIG. 2 is a perspective view thereof.

The broken line disclosure of the remainder of the dual EAS-RFID tag in the figures are shown for illustrative purposes only and form no part of the claimed design.
